ATTORNEY

UNITED STATES PATENT OFFICE

133,135

DESIGN FOR A BADGE OR SIMILAR ARTICLE

Joseph Stellitano, Jamaica, N. Y.

Application December 16, 1941, Serial No. 104,660

Term of patent 7 years

To all whom it may concern:

Be it known that I, Joseph Stellitano, a citizen of the United States, residing at 147-16 Ferndale Avenue, Jamaica, Long Island, New York, have invented a new, original, and ornamental Design for a Badge or Similar Article, of which the following is a specification, reference being had to the accompanying drawing, forming a part thereof.

Fig. 1 is a plan view of a badge showing my new design.

Fig. 2 is an end view of the same.

I claim:

The ornamental design for a badge or similar article, as shown.

JOSEPH STELLITANO.
